CLAIM

The ornamental design for an ice cube tray, as shown and described.

DESCRIPTION

FIG. 1 is a top, front, left perspective view of the ice cube tray showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken line showing in the figures is for the purpose of illustrating portions of the ice cube tray that forms no part of the claimed design.
